CLOSURE FASTENER

Michael Marus, Plant City, Fla.

Application May 2, 1946; Serial No. 666,622

4 Claims. (Cl. 292—246)

1.

This invention relates to improvements in fastening devices and particularly to inexpensive latch type fastening devices for crates, hampers, boxes and cartons used as containers for various kinds of agricultural produce and products of manufacture. The device may also have other uses such as for connecting the ends of certain types of belts, and connecting the edges of fabric tents and awnings, and the device may be used in any combination in which its construction is of particular advantage without in any way exceeding the scope of the invention.

It is therefore among the objects of the present invention to provide a closure fastener formed of wire, that is simple and inexpensive to manufacture, easy to install, has no sharp projections, is easy to latch and unlatch, and is sufficiently strong to retain the top or lid on a hamper or other container under all normal handling and shipping conditions and to provide in addition a large safety factor so that if the container were subjected to accidental violence it would not ordinarily be broken open.

Another object resides in the provision of an improved closure fastener in which two staples like portions are releasably secured together by a wrapped wire loop to provide a strong and durable connection.

Other objects and advantages will be more particularly pointed out hereinafter or will become apparent as the description proceeds in connection with the accompanying drawings.

In the drawings:

Fig. 1 is a perspective view of the improved closure fastener in unlocked position; and

Fig. 2 is a view similar to Fig. 1 showing the fastener in locked position.

With continued reference to the drawings, the fastener is shown attached to a container having a body wall portion 10 and a top or lid portion 11. A generally U-shaped staple member 12 having a substantially straight intermediate portion 13 and leg portions 14 and 15, extending at right angles to the intermediate portion and substantially parallel to each other, is secured to the wall portion 10 by having the end portions of the legs 14 and 15 bent inwardly at right angles and extended through the wall, as indicated at 16 and 17. The ends of the staple may be bent up or clenched over, as indicated at 18 and 19, to securely lock the staple in the wall. If desired, the ends of the staple may be sharpened so that they may be easily forced through the material of the container wall. It will be noted that the staple is located on the outside of the wall and

the sharpened ends on the inside where they are clenched over in such a manner that there are no sharp extensions or projections which could cause bodily injuries or clothing damage to a person handling or using the container.

Another U-shaped staple 20 having a substantially straight intermediate portion 21 and parallel leg portions 22 and 23, is secured to the container closure or lid 11 in such a manner that the intermediate portion of the staple is spaced outwardly from the adjacent edge of the lid a distance slightly greater than the thickness of the wall 10.

The staple 20 is secured to the closure 11 by having end portions of the legs 12 and 13 bent at right angles as indicated at 24 and 25 and forced through the thickness of the closure, after which the projecting portions of the staple ends are bent over or clenched at right angles to the portions projecting through the closure as indicated at 26 and 27. While it is preferred that the bent over end portions 26 and 27 extend in the same general direction as the staple legs 22 and 23 in order that they may better distribute the reactive force from the staple over the inner surface of the lid or closure they may be bent or clenched at any other desired angle without in any way exceeding the scope of the invention.

The legs 22 and 23 are also bent at right angles at a location adjacent to the intermediate member 21 as indicated at 28. This bend positions the intermediate portion 21 somewhat below the upper surface of the lid or closure 11 and in or near the plane of the lower surface of the closure so that no part of the fastener extends above the top of the container. With this arrangement containers may be stacked one on top of the other without any interference with the closure fasteners.

It will be noted that the intermediate portion 13 of staple 12 is considerably longer than the corresponding intermediate portion 21 of staple 20. On the intermediate portion 13 of staple 12 there is pivotally mounted a latch member generally indicated at 30. This member has an intermediate portion or tongue 31 of U-shape or hairpin shape and has its end portions wrapped about the intermediate portion of the staple 13, as indicated at 32 and 33. The wrapped portions of the latch member 31 each provide at least one complete turn about the staple and each wrapped portion extends outwardly from the adjacent side of the intermediate portion 31 of the latch. The loops comprising the wrapped portions 32 and 33 are sufficiently loose on the intermediate portion

of staple 12 so that the intermediate portions of both staples 12 and 20 may be included in the loops thereof.

The staples 12 and 20 are preferably formed of relatively heavy, stiff wire which will not spring or bend substantially under normal loads to which the fastener is subjected. The latch 30 may be made of a lighter wire which may also be somewhat softer to facilitate the wrapping of the ends of the latch member about the intermediate portions of staple 12, this type of wire being sufficiently strong and stiff for the latch member, since it supports the loads by means of two relatively small loops which are not likely to bend or pull out.

In order to lock the closure fastener the tongue 31 of the latch member in the upright position illustrated in Fig. 1 is inserted through the upper staple 20 and is then turned downwardly to the position illustrated in Fig. 2. As the tongue is turned downwardly it will turn over the intermediate portion of the upper staple and bring the intermediate portion of the upper staple into the loops of the wrapped portions 32 and 33 of the latch, as is clearly illustrated in Fig. 2. When the latch is turned downwardly to its locked position, its ends are turned inwardly toward the lid or closure 11 and do not project outwardly from the container. There are thus no points or projections extending outwardly from the fastener when in its locked position and the container to which it is applied may be handled safely without any danger of damage to the clothing or person of anyone handling the containers. The container lid or cover is also securely locked down and will not be accidentally released under normal usage or even when the container is subjected to accidental violence unless the violence is of such a degree as to break other parts of the container.

It will be obvious to those skilled in the art that various changes may be made in the invention without departing from the spirit and scope thereof and therefore the invention is not limited by that which is shown in the drawings and described in the specification but only as indicated in the appended claims.

What is claimed is:

1. A closure fastener comprising two wire staple members having substantially straight intermediate portions, and a latch member pivoted on the intermediate portion of one of said staple members and comprising an intermediate portion of hairpin shape, and end portions wrapped about the staple member loosely enough to include the intermediate portions of both staple members therein, whereby said hairpin shaped intermediate portion of the latch member may be inserted through the other of said staple members and turned downwardly to include both staple members in the loops of the wrapped end portions of said latch.

2. A closure fastener comprising a pair of U-shaped staples having substantially straight intermediate portions and legs extending at right angles thereto, a latch member pivotally secured on the intermediate portion of one of said staples for operative engagement with the intermediate portion of the other staple, said other staple having the end portions of its legs bent at right angles to pass through a container lid or closure and then bent over or clenched on the inner side of the container closure and also having its legs bent at right angles at a location adjacent to said intermediate portion to bring said intermediate portion into or near the plane of the inner surface of said closure.

3. A closure fastener comprising a pair of U-shaped staples having substantially straight intermediate portions and parallel leg portions extending at right angles to the intermediate portions and a latch member pivotally secured on the intermediate portion of one of said staples for operative engagement with the other of said staples; said other staple having the end portions of its legs bent at right angles to pass through a wall of a container and bent over or clenched at the inner surface of said wall, and said latch member having its end portions wrapped about the intermediate portion of said one staple to provide loops to enclose the intermediate portions of both staples when the fastener is in locked condition.

4. A closure fastener comprising a pair of generally U-shaped staple members having substantially straight intermediate portions and parallel legs extending at right angles from said intermediate portions, one of said staple members being attachable to a container closure and the other to a container wall, and one of said members having a longer intermediate portion than the other; a latch member having an elongated U-shaped tongue portion and end portions wrapped about the intermediate portion of said one staple to provide a complete loop at each side of said tongue portion, said tongue portion being inserted through said other staple and rotatable about the intermediate portions of both staples to bring said intermediate portions within said loops, the ends of said latch being directed toward the closure member of a container when the fastener is mounted on a container and in locked condition.
